BOLTLESS RAIL-JOINT.

1,255,722.

Specification of Letters Patent. Patented Feb. 5, 1918.

Application filed July 31, 1917. Serial No. 183,697.

To all whom it may concern:

Be it known that I, CHARLES ENGELLAND, a citizen of the United States, residing at Tampa, in the county of Hillsborough and 5 State of Florida, have invented certain new and useful Improvements in Boltless Rail-Joints, of which the following is a specification.

My invention relates to new and useful 10 improvements in scarf-joints, and has for its primary object the provision of a scarf-joint structure particularly adapted for use as a rail joint although I do not wish to in any way limit myself to such use as it may be employed with good results in carpentry, ship 15 building and in steel structures.

One of the objects of my present invention consists in providing a scarf-joint structure for rail joints which will do away with the 20 use of fish plates, chair plates, bolts and other fastening means now commonly employed in rail joints.

Another object which I have in view is the construction of an interlocking scarf-joint 25 in which a single key, generally in the form of a spike serves to secure the joint and also to anchor the jointed rail ends to a supporting cross-tie.

A still further object of my invention consists in the provision of a joint and key for locking the joint, of such a character that a key of one size may be employed to lock the joint and still leave a certain amount of play to allow for expansion and contraction of 35 the members locked or in which a key of somewhat larger size may be employed to absolutely prevent any play between the parts joined.

With these and other objects in view, my 40 invention will be more fully described, illustrated in the accompanying drawings, and then specifically pointed out in the claims which are attached to and form a part of this application.

45 In the drawings:

Figure 1 is a fragmentary perspective view illustrating my improved scarf-joint as a connecting means between adjacent rail ends, showing the spiking and keying element which serves to secure the rail ends together and to the cross tie;

Fig. 2 is a fragmentary horizontal sectional view taken on the line 2—2 of Fig. 1, looking in the direction of the arrows;

55 Fig. 3 is a perspective view of a rail end

constructed in accordance with my present invention, a spiking and keying element being also shown in this view;

Fig. 4 is a fragmentary perspective view illustrating the use of my improved scarf-joint in structural steel work;

Fig. 5 is a transverse sectional view taken on the line 5—5 of Fig. 4;

Fig. 6 is a sectional view taken on the line 6—6 of Fig. 5.

Corresponding and like parts are referred to in the following description and indicated in all the views of the drawings by the same reference characters.

In order to insure a clear and accurate 70 understanding of my scarf-joint structure I have disclosed it in connection with a pair of rails 10 and 11 which are connected by the joint and which are supported upon a cross tie 12, other cross ties, not shown, of course 75 supporting more remote portions of the rails.

In constructing rails to be joined by my improved joint the rails for a suitable distance at their ends have their web portions 80 offset, as shown at 14, to provide abutting inner faces 15, nearly in the plane of the opposite faces of the remaining portions of the webs, which will engage each other when the rails are placed end to end with 85 such portions overlapping. The heads 16 and flanges 17 of the rails for a short distance at the ends and at the same side as these abutting faces are cut-away to provide upper and lower locking shoulders 18 90 and 19 respectively, projecting beyond the abutting faces with their outer bearing faces in substantially the plane of the faces of the webs proper of the rails at the same side. The ends of these shoulders are extended 95 beyond the ends of the rails to provide upper and lower locking tongues 20 and 21 respectively.

Longitudinally extending rectangular slots 22 and 23 are formed in the heads and 100 bases of the rails just inside of these shoulders and of greater length than the shoulders but of the same depth and width, and the heads and flanges of the rail ends at the same side as the shoulders are cut-away 105 to a point near the inner ends of the slots whereby the slots, save at their inner ends, are opened out into the overlapping faces of the rail ends so that the upper and lower shoulders 20 and 21 of one rail end may 110

engage in the upper and lower slots or seats 22 and 23 of the other rail end with the lower and upper faces of the shoulders 18 and 19 respectively, engaging the bases 5 of the upper and lower slots or seats.

The tongues 20 and 21 are so proportioned that under such circumstances when the end face of the uncut-away side of the head of one rail engages against the end face 10 of the cut-away side of the head of the other rail, as shown in Fig. 1, the ends of the tongues will engage the inner ends of the slots or seats. Obviously, inasmuch as the slots or seats are of greater length than the 15 locking shoulders the rail ends may be brought into overlapping engagement with the shoulders seating in the outer ends of the seats after which one rail may be moved longitudinally toward the other to bring the 20 shoulders into the ends of the seats, as shown in Fig. 1, when the joint will be assembled.

When so assembled the bearing faces of the shoulders 18 and 19 of each rail end 25 engage the inner faces of the seats 22 and 23 respectively, of the other rail end, and the abutting faces 15 of the rail ends engage each other. The lower and upper faces of the shoulders 18 and 19 respectively engaging 30 against the bases of the seats hold the rail ends against independent vertical movement while the tongues 20 and 21 engaging in the inner or closed ends of the seats or slots 22 and 23 respectively, hold the rail 35 ends in alignment.

The abutting inner faces 15 of the rail ends are formed with vertical channels 24 at the inner ends of the shoulders 18 and 19, which open into the outer ends of the 40 upper and lower slots or seats 22 and 23. When the joint is assembled the spaces between the outer ends of the seats and inner ends of the shoulders and these channels aligned with each other provide a vertical 45 key or spike receiving opening 25 extending completely through the interlocking rail ends so that a key in the form of a spike 26 may be passed through the opening and driven into the cross tie 12 to lock the 50 rails to the tie and against longitudinal movement away from each other.

Preferably the opening thus formed is 55 rectangular in cross section to receive a correspondingly shaped spike and the shank of the spike 26 should be somewhat narrower than the length of the opening to permit some play in the joint and so allow for expansion and contraction of the rails under changes in temperature. The spike 60 preferably has a somewhat tapering chisel point 27 and the portion of the spike which is to engage in the tie may be formed with barbs 28. Also the spike at the end opposite its point is formed at its side edges 65 with projecting head forming shoulders 29,

the under faces of which are inclined as shown. The outer end walls of the slots 22 are cut-away as shown at 30, to provide seats for the head 31 formed by the shoulders 29 so that the spike may be countersunk in the joint, as clearly shown in Fig. 1. 70

Obviously, with rails formed in this manner a track may be rapidly laid as practically no time is consumed in joining the ends of adjacent rails. Furthermore, the 75 cost of laying the track is materially decreased due to the fact that no bolts, nuts, fish-plates, chair-plates and the like are necessary. Because of the engagement of the edges of the shoulders with the bases 80 of the seats and because of the further fact that portions of the flanges or bases of both rails engage the same tie all pounding of the joint is prevented. Inasmuch as the anchoring key or spike is passed through 85 the heads of the joined rail sections it will be clear that any tendency which it might have to work loose will be overcome due to the passage of wheels along the rails.

An inspection of the drawings will disclose the fact that this joint is also adapted 90 for use in carpentry, ship building and steel construction. For instance, in Figs. 4, 5 and 6 I have illustrated the use of my improved joint, there indicated as a whole 95 by the numeral 32, as a means for connecting abutting ends of I-beam sections 33 and 34. The construction of the joint is identical with that previously described but the locking key 35 has its free end threaded as 100 shown at 36 to receive a nut 37. Furthermore, the shank of this key is proportioned to fit snugly in its opening so as to prevent any independent movement of the parts.

Particular attention is directed to the 105 fact that the construction of all the rail ends is identical so that there is no difficulty in assembling the rails. Furthermore, this duplicate construction greatly decreases the cost of manufacture as less machinery and 110 less diversity of labor is required.

Having thus described the invention, what is claimed as new is:

1. In a scarf-joint, a pair of members to be joined each formed at the end with spaced shoulders and tongues and with corresponding seats having extensions whereby when the members are assembled with their ends overlapping the shoulders and tongues of each member will lockingly engage in 120 the seats and their extensions of the other member, the overlapping faces of the members being formed with channels which align to provide an opening, and a key passed through the opening to secure the members 125 against displacement.

2. In a scarf-joint, a pair of members to be joined each formed at the end with spaced shoulders and tongues and with corresponding seats having extensions whereby when 130

the members are assembled with their ends overlapping the shoulders and tongues of each member will lockingly engage in the seats and their extensions of the other member, the overlapping faces of the members being formed with channels which aline to provide an opening, and a key passed through the opening to secure the members against displacement, the shoulders, tongues and seats and their extensions of one member being counterparts of those of the other member.

3. In a scarf-joint, a pair of members to be joined each formed at the end with upper and lower shoulders and with tongues projecting beyond the ends and forming continuations of such shoulders and with seats adjacent the inner ends of the tongues, a portion of the seats being open whereby when the members are placed with their ends overlapping the shoulders and tongues of each member may be engaged in the seats of the other member and moved to bring the projecting tongues into the unopened portions of the seats whereby the tongues hold the members against swinging movement and engagement of the shoulders against the bases of the seats holds the members against independent vertical movement, the overlapping end portions of the members being formed with channels adapted to aline when the members are assembled and a key insertible in the alined channels to hold the members against movement away from each other.

4. In a rail joint, rail ends each having its web portion near its end offset and its head and flange portion cut-away to provide shoulders projecting beyond the inner faces of the offset portions of the webs at

the free ends of the rail sections and to further provide tongues projecting beyond such ends and forming continuations of the shoulders, the rail sections adjacent the inner ends of the shoulders being formed with longitudinal slots in the head and base portions and having their head and flange portions further cut-away whereby the slots save at their inner ends, open out through the inner faces of the rail sections to provide seats, the forming of the end portions of the rail sections being such that the shoulders of each section will engage in the seats of the other section with the tongues engaging in the unopened ends of the seats, and a spiking and keying element passed into an opening provided by channeling the overlapping faces of the rail sections adjacent the shoulders whereby the opening alines with the outer ends of the seats beyond the inner ends of the shoulders, the head of the element being counter-sunk in the head portion of the rail sections forming the joint.

5. In a rail joint, a pair of rail sections to be joined each formed at the end with spaced shoulders and tongues and with corresponding seats having extensions whereby the ends of the rail sections may be overlapped to seat the shoulders and tongues of one in the seats and extensions of the other, the engaging faces of the rail sections when so assembled being formed with channels which aline, and a spike fitting loosely in the alined channels to act as a key to secure the rail sections together, the spike being adapted to be driven into a supporting cross tie.

In testimony whereof I affix my signature.
CHAS. ENGELLAND. [L.s.]
